United States Patent Office.

THOMAS H. DUNHAM, OF BOSTON, MASSACHUSETTS.

Letters Patent No. 64,084, dated April 23, 1867.

IMPROVEMENT IN CARPET-WADDING.

The Schedule referred to in these Letters Patent and making part of the same.

TO ALL WHOM IT MAY CONCERN:

Be it known that I, THOMAS H. DUNHAM, of Boston, in the county of Suffolk, and State of Massachusetts, have invented a new and useful Improvement in Carpet-Wadding, the same being a new article of manufacture; and I do hereby declare that the following is a full and exact description of the same, and of one mode or process that may be employed in its manufacture, reference being had to the accompanying drawing, and to the letters and figures marked thereon.

Figure I is a plan or top view of a piece of the carpet-wadding.

Figure II is a vertical section of the same.

I will first refer to Letters Patent of the United States granted to me on the first day of May, A. D. 1866, and numbered 54,312, for an improvement in carpet-wadding, the same being a new article of manufacture, produced by uniting a bat or layer of cotton, or other fibre, to paper, by causing it to be delivered or laid upon the newly-formed web or continuous sheet of paper which has just been formed from the pulp in a paper machine. In the article thus made the fibrous material adheres to the paper without the use of gums or any adhesive substances.

The new article that I have produced is the same as that above referred to, so far as relates to the adhesion or attachment of the batting or sheet of fibre to the paper, the improvement in the same having reference exclusively to the selvedge, margin, or border which forms the outer edges of the sheet of finished wadding, two or more sheets of paper being closed together while in the moist condition above referred to, thus enclosing the sheet of fibre in a flat bag or sack, and preventing the exposure of the edge of the bat, the escape of dust, and the entrance of moths and other insects.

In the figures, the direction of the length is represented by the arrows, and the breadth of the wadding is shown between A and B. The bat or fibre L is narrower than the paper, occupying the space from G to G'. Outside of this, to the right and left, are the two selvedges, or borders H and J, formed by compressing or closing the edges of the sheets of paper together. This may be done by means of narrow rollers or other suitable mechanism while the paper is still moist, and before it becomes hard by exposure to the air or by drying with artificial heat. In some cases I prefer to make the selvedge or border in corrugated form, as represented at H, thus causing the contact of a larger surface of paper and a firmer adhesion of the sheets. Either the plain or corrugated edge or border may be used, as preferred, while the main features of the invention are retained, viz, the enclosure of a sheet of batting or soft fibrous substance between sheets of paper united at the outer edges or selvedge while the paper is in a moist condition, as above stated. By the use of very strong and thin paper and a bat or sheet of wool, hair, or other animal fibre, I prepare a thin and light kind of wadding suitable for use in clothing that requires to be stuffed or padded. It is not liable to slide upon the paper, and when packed or stored in bales in readiness for sale or use, it remains in good order for any length of time, as no moths can obtain access to the enclosed fibre.

What I claim, and desire to secure by Letters Patent, is—

A wadding or fabric, having an adherent border or selvedge formed of the sheets of paper that project beyond the edges of the batting, and attached to each other, as herein specified, without the use of gum or other adhesive substance, substantially as described.

THOMAS H. DUNHAM. [L. S.]

In presence of—

JOHN M. BATCHELDER,
EBEN T. GRAY.
